pany, St. Louis, Mo.

Application October 30, 1946, Serial No. 706,531

11 Claims. (Cl. 225—21)

1

This invention relates in general to certain new and useful improvements in carbonated beverage dispensing valves.

It is the primary object of the present invention to provide a carbonated beverage dispensing valve which is simple and compact in construction and which can be readily attached to any existing beverage dispensing system.

It is a further object of the present invention to provide a valve of the type stated which is capable of optionally dispensing a properly proportioned flavored carbonated drink or unflavored carbonated water, as desired.

It is an additional object of the present invention to provide a valve of the type stated which is capable of dispensing carbonated water without appreciable loss of gaseous carbon dioxide, thereby supplying a carbonated drink having an unusually high degree of retained carbonation.

It is also an object of the present invention to provide a valve of the type stated which can be precisely adjusted to throttle the flow of carbonated water at any desired rate within substantially broad limits.

It is likewise an object of the present invention to provide a valve of the type stated which can be readily and quickly dismantled and reassembled for replacement of washer and any other similar parts.

And with the above and other objects in view, my invention resides in the novel features of form, construction, arrangement, and combination of parts presently described and pointed out in the claims.

In the accompanying drawings:

Figure 1 is a perspective view of a preferred form of carbonated beverage dispensing valve constructed in accordance with and embodying the present invention;

Figure 2 is a vertical sectional view of the beverage dispensing valve taken along line 2—2 of Figure 1;

Figures 3 and 4 are transverse sectional views of the valve taken along lines 3—3 and 4—4, respectively, of Figure 2;

Figures 5 and 6 are fragmentary sectional views taken along lines 5—5 and 6—6, respectively, of Figure 4;

Figure 7 is a vertical sectional view showing the valve in position for dispensing a flavored beverage;

Figure 8 is a fragmentary sectional view taken along line 8—8 of Figure 7;

Figure 9 is a vertical view showing the valve in position for dispensing carbonated water only; and

Figure 10 is a fragmentary sectional view taken along line 10—10 of Figure 9.

Referring now in more detail and by reference characters to the drawings which illustrate a preferred embodiment of the present invention, A designates a carbonated beverage dispensing valve comprising a solid, preferably stainless steel, valve-body 1 of rectangular shape having a bottom face 2, a top face 3, side faces 4, 4', a front end-face 5, and a rear end face 6. Opening upon the bottom face 2 and extending upwardly into the valve body 1, midway between the side faces 4, 4', is a large-diameter recess 7 having a flat horizontal top wall 8 and being internally threaded adjacent its lower end, as at 9. Drilled concentrically in the bottom wall 8 and extending axially upwardly therefrom is a bore 10, which is successively concentrically drilled in the provision of a poppet guide recess 11 and counter-bored thereby providing a valve chamber 12, and a collar recess 13, the latter being of slightly larger diameter than the valve chamber 12 in the formation of an annular shoulder 14. Drilled horizontally inwardly from the rear end face 6 of the valve body 1 is a bore 15 intersecting, on its inner side face, the valve chamber 12 and opening thereto, as at 16. Adjacent its outer end, the bore 15 is internally threaded for receiving a conventional fitting 17, which is, in turn, connected to a carbonated water supply line 18.

Threadedly mounted in the recess 7 is a nozzle member 19 bearing along its upper margin against the downwardly presented margin of a nozzle cup 19' snugly disposed within the upper portion of the recess 7 and having a relatively thick bottom wall 20, the upper face 21 of which is normally spaced slightly downwardly from the bottom face 8 of the recess 7. At its lower end, the nozzle 19 projects downwardly below the bottom face 2 and is tapered inwardly slightly in the provision of a nozzle skirt 22 having a discharge orifice 23 of somewhat reduced diametral size. Upon its upper face 21, the nozzle member 19 is concentrically drilled to provide an axially extending discharge passage 24, which is, in turn, counter-bored at its upper end in the provision of a diametrically enlarged collar recess 25 of the same diametral size and aligned with the collar recess 13 for retaining a tubular rubber ring or collar 26, which, in normal unstressed condition, has an outside diametral size equal to the diametral size of the recesses 13, 25, and an inside diametral size identical with the diametral size of the passage 24 having a vertical height somewhat greater than the combined vertical dimensions of the recesses 13, 25, all as best seen in Figures

2, 7, and 9 and for purposes presently more fully appearing.

Upon its under or downwardly presented face, the bottom wall 20 is provided with two concentrical round-bottomed grooves 27, 28, which are, in effect, separated from each other and from the discharge passage 24 by depending concentric round-topped ridges 29, 30, so that in horizontal cross-section the grooves and ridges 27, 28, 29, 30, will present a sinuous contour, as shown in Figures 2, 7, and 9.

Shiftably mounted concentrically within the discharge passage 24 is a valve stem 31 rigidly provided at its upper end with a shouldered poppet 32 having an upwardly projecting guide stem 33 extending into the poppet guide-recess 11 and being normally urged downwardly by means of a compression spring 34 into seated engagement against the upper face of the rubber collar 26. At its lower end, the stem 31 projects downwardly beyond the discharge passage 24 and is threaded for receiving a downwardly pointed concentric cone 35, the apex of which is normally located just above the plane of the discharge nozzle 23.

Extending horizontally in and projecting radially outwardly from the side faces of the cone 35, at an angle of approximately 120° to each other, are three round-ended guide pins 36 adapted to ride loosely against the inner face of the nozzle 19 for holding the cone 35 and its associated valve stem 31 in substantially concentric alignment during upward and downward movement. Upon its upper end face, the cone 35 is provided with upwardly projecting concentric round-topped ridges 37, 38, and round-bottomed grooves 39, 40, respectively matching and complementarily fitting within and around the grooves and ridges 27, 28, 29, 30, of the nozzle member 19. Extending vertically through the valve body 1, in spaced parallel relation to the recess 7 and adjacent to the front end face 5, is a bore 41 opening at its upper end upon the upper end face 3 and being internally threaded for a short distance downwardly therefrom to threadedly receive a flat disk-like end plug 42, which is centrally bored and counter-bored in the provision of a check valve port 43 and a downwardly opening ball socket 44. About midway of the valve body 1, the bore 41 is reduced in diametral size in the provision of a shoulder 45 having a raised annular valve seat 46, and, in effect, forming a valve chamber 47 within the upper end of the bore 41.

Snugly fitted within the lower or reduced-size end of the bore 41 for lengthwise shiftable, but leakproof movement therein, is a syrup discharging spout 48, which, at its upper end, projects upwardly into the valve chamber 47 and in diametrically enlarged and undercut for receiving a downwardly presented annular ring washer 49 for seated engagement against the valve seat 46. Upon its upper end face the spout 48 is provided with a slightly raised concentric projection 50 for receiving the lower end of a compression spring 51, which is, in turn, at its upper end retentively seated against the under side of a small check valve ball 52 operatively disposed within the recess 44 for seated engagement within the port 43. Directly beneath the region of the ring washer 49, the spout 48 is turned to a slightly reduced diametral size and is provided with a plurality of radially extending orifices 53 connecting the interior of the spout 48 with the interior of the valve chamber 47 when the spout 48 is lifted to the position shown in Figure 7.

Opening upon the rear face 6 of the valve body

1 and extending horizontally thereinto, in spaced parallel relation to the bore 15, is a bore 54 at its forward end intersecting the side wall of and opening into the valve chamber 47 and being internally threaded at its rearward end for receiving a conventional fitting 55 connected to a syrup supply line 56.

At its lower end, the spout 48 projects downwardly below the bottom wall 2 of the valve body 1 and terminates in a discharge orifice 57 which is normally in coplanar alignment with the discharge orifice 23 of the nozzle member 19 when the valve A is in closed position, as shown in Figure 9.

The syrup spout 48, for a short portion of its length entirely within the reduced-size portion of the bore 41 and upwardly from the bottom wall 2 of the valve body 1, is turned to a somewhat reduced diameter in the provision of an annular recess or groove 58. In the same region or area, the valve body 1 is provided with a transversely extending horizontal bore 59 opening at its opposite ends upon the side faces 4, 4', and an intersecting angular bore 60, the center line 20 of which is approximately in the same plane as, and at an angle of 120° to, the center lines of the pins 36. Snugly and rotatively fitted within the bore 59, in the region of its intersection with the bore 60, is an actuator pin 61 provided at its inner end with an angularly cut flat cam section 62, the latter being located within the common area of intersection between the bores 59, 60. Upon the outer end face, the pin 61 is flush with the side face 4' of the valve body 1 and is integrally provided with an outwardly projecting flat-sided attachment boss 63. Also snugly and rotatively fitted within the bore 59 and extending inwardly from the side face 4 of the valve body 1, is a second actuator pin 64 terminating at its inner end just short of the syrup spout 48 and being provided with an axially projecting eccentrically located pin-like projection 65 adapted to fit within the spout-groove 58. At its outer end, the pin 64 is substantially flush with the side face 30 30 35 40 45 50 55 60 65 70 75 80 85 90 95 4 of the valve body 1 and is integrally provided with a flat-sided boss 66. Fixed upon the bosses 63, 66, and secured thereto by flat-headed retainer screws 67, 68, which are threaded axially into the actuator pins 61, 64, respectively, is a clevis-shaped dispensing handle 69 which extends outwardly beyond the front end face 5 of the valve body 1 and is preferably provided with an inserted rectangular Bakelite block 70 which serves as an artistic hand grip or knob and is held in place by a tubular sleeve 71 extending between the parallel side arms of the clevis-shaped handle 69 and being threaded at its opposite ends for receiving flat-headed retainer screws 72, 73.

Extending through the angular bore 60 and inserted within the cone 35 is a cone actuating pin 74 which rests upon the upwardly presented flat camming face of the actuator pin 61, the bore 60 being finally closed by a threaded end plug 75.

In actual use, the nozzle member 19 may be threaded upwardly, thereby shifting the nozzle cup 19' upwardly and axially shortening or compressing the rubber collar 26, causing it to bulge inwardly, as shown in Figure 2, thereby reducing or throttling the size of the discharge passage to control the rate of flow of carbonated water therethrough. The inward bulging of the rubber collar 26 will also produce a Venturi-like or streamline constriction at the throttling point in

the valve so that the flow of carbonated water through the constricted area will be substantially non-turbulent and the gas content thereof will not be lost or "scrubbed out," so to speak.

It will thus be seen by a simple manual rotation of the nozzle 19, it is possible to achieve very accurate adjustment in this respect. This particular adjustment is unique and extremely important in a beverage dispensing valve because the rate of flow of syrup is not readily controllable and will flow at a rate, which, for all practical purposes, is fairly constant for a substantial period of time. The rate of flow of the syrup will, of course, vary in proportion to variations in the hydrostatic head of the syrup contained in the syrup reservoir or storage tank (not shown), but, due to the relatively high viscosity of the syrup, the effect of such hydrostatic head is not particularly critical. However, the syrup will flow somewhat faster when the storage tank is full and consequently a somewhat greater quantity of syrup will, under such condition, be dispensed in a given unit of time and a carbonated drink will have a greater proportion of flavoring syrup than a drink which is made when the storage tank is relatively empty. With the present beverage dispensing valve A, this variation can be very quickly and conveniently compensated by the throttling adjustment of the discharge passage 24. For example, in the case of a soda fountain or soft drink dispensing bar equipped with the valve A, where the syrup storage tank must be filled every two or three days, it will merely be necessary to make a throttling adjustment once every day or so, reducing the rate of flow of the carbonated water slightly as the rate of flow of syrup is reduced. In commercial practice at the ordinary drug store, soda fountain, and the like, a customer frequently requests that his drink be made up "sweet" or "dry," that is to say, with either more or less than the usual amount of flavoring syrup and the soda dispenser can easily comply with such request by a simple twist of the nozzle member 19 without any loss of time or inconvenience.

When it is desired to dispense a syrup-flavored drink, the handle 69 is pushed downwardly, as shown in Figure 7, rotating the actuator pins 61, 64, whereupon the camming surface 62 lifts the pin 74, cone 35, the associated valve stem 31, and the poppet 32 to permit the flow of carbonated water downwardly through the discharge passage 24 past the concentric convolutions of the nozzle cup 19' and the end face of cone 35, downwardly through the nozzle member 19 and outwardly through the orifice thereof. At the same time, the pin-like projection 65 of the actuator pin 64 is swung eccentrically upwardly, lifting the spout 48 and thereby allowing the syrup to flow from the chamber 47 through the orifices 53, downwardly through the interior of the spout 48, and outwardly from the discharge orifice 57 thereof. The discharging syrup and carbonated water will flow simultaneously downwardly into a glass or other drink receptacle and will be thoroughly intermixed.

When it is desired to dispense unflavored or plain carbonated water, the handle 69 is shifted upwardly, as shown in Figure 9, rotating the actuator pins 61, 64, in the opposite direction. Inasmuch as the camming surface 62 of the actuator pin 61 is flat, it will lift the pins 74 when rotated in either direction. Thus, when the handle 69 is swung upwardly and the actuator pin 61 is rotated thereby, the pins 74 and the associated component parts of the carbon-

ated beverage valve mechanism will be opened to permit the flow of carbonated water. However, the upward swinging movement of the handle 69 will rotate the actuator pin 64 in such a manner that the pin-like projection 65 will swing downwardly away from abutment with the shoulder formed by the groove 58 in the syrup spout 48, as best seen in Figure 10, and will thus leave the latter stationary, so that no syrup will be discharged.

By reason of the concentric convolutions formed between the concentric grooves and ridges 21, 28, 29, 30, 37, 38, 39, 40, of the downwardly presented face of the nozzle cup 19' and the upwardly presented face of the cone 35, respectively, the carbonated water issuing from the discharge passage 24 will undergo a somewhat gradual decrease in pressure and will be substantially non-turbulent in character, with the result that the entrained and dissolved carbon dioxide gas will not be scrubbed out and lost in any appreciable quantity as the carbonated water flows into the glass or drinking receptacle. For this reason, the carbonated water dispensed from a valve constructed in accordance with the present invention will have a much higher percentage of residual carbonation than will carbonated water dispensed from conventional faucets.

It should be understood that changes and modifications in the form, construction, arrangement, and combination of the several parts of the dispensing valve may be made and substituted for those herein shown and described without departing from the nature and principle of my invention.

Having thus described my invention, what I claim and desire to secure by Letters Patent is:

1. A valve for controlling the flow of fluids comprising a valve body having first and second passages extending therethrough, said first passage being constricted intermediate its ends in the provision of a valve seat, a tubular spout slidably mounted in one end of said first passage and projecting inwardly beyond the constriction, being provided on such inwardly projecting end with a closure element for valve-forming co-operation with the valve seat, a tubular member mounted in and projecting from the lower end of said second passage and being provided at its upper end with a valve seat forming end face, a stem loosely and shiftably mounted in and extending through said tubular member, a valve poppet fixed upon the upper end of said stem for co-operation with the seat forming end face, and handle means for simultaneously lifting the spout, stem, and the associated closure element and poppet for opening both of said passages and permitting the flow of fluids therethrough.

2. A valve for controlling the flow of fluids comprising a valve body having first and second passages extending therethrough, said first passage being constricted intermediate its ends in the provision of a valve seat, a tubular spout slidably mounted in one end of said first passage and projecting inwardly beyond the constriction, being provided on such inwardly projecting end with a closure element for valve-forming co-operation with the valve seat, a tubular member mounted in and projecting from the lower end of said second passage and being provided at its upper end with a valve seat forming end face, a stem loosely and shiftably mounted in and extending through said tubular

member, a valve poppet fixed upon the upper end of said stem for co-operation with the seat forming end face, and handle means mounted upon the valve body for swingable movement in two directions and being adapted, upon movement in one such direction, for simultaneously lifting the spout, stem and the associated closure element and poppet for opening both of said passages and permitting the flow of fluids therethrough and being further adapted, upon movement in the other direction, for lifting only the stem of its associated poppet for permitting flow of fluids through the second passage only.

3. A valve for controlling the flow of fluids comprising a valve body having first and second passages extending therethrough, said first passage being constricted intermediate its ends in the provision of a valve seat, a tubular spout slidably mounted in one end of said first passage and projecting inwardly beyond the constriction, being provided on such inwardly projecting end with a closure element for valve-forming co-operation with the valve seat, a tubular member mounted in the lower end of said second passage and being provided at its upper end with a valve seat forming end face, a stem loosely and shiftably mounted in and extending through said tubular member, a valve poppet fixed upon the upper end of said stem for co-operation with the seat forming end face, a discharge nozzle mounted on the valve body and projecting downwardly from the tubular member, a downwardly pointed cone-shaped member disposed within the nozzle and being connected to the stem for movement therewith, an abutment shoulder on the spout, actuating means on the cone-shaped member, a pair of pins rockably mounted in the body for operative engagement respectively with the shoulder and actuating means, and handle means mounted on the pins for rocking the pins and thereby simultaneously lifting the spout, stem and the associated closure element and poppet for opening both of said passages and permitting the flow of fluids therethrough.

4. A valve for controlling the flow of fluids comprising a valve body having first and second passages extending therethrough, said first passage being constricted intermediate its ends in the provision of a valve seat, a tubular spout slidably mounted in one end of said first passage and projecting inwardly beyond the constriction, being provided on such inwardly projecting end with a closure element for valve-forming co-operation with the valve seat, a tubular member mounted in the lower end of said second passage and being provided at its upper end with a valve seat forming end face, a stem loosely and shiftably mounted in and extending through said tubular member, a valve poppet fixed upon the upper end of said stem for co-operation with the seat forming end face, a discharge nozzle mounted on the valve body and projecting downwardly from the tubular member, a downwardly pointed cone-shaped member disposed within the nozzle and being connected to the stem for movement therewith, an abutment shoulder on the spout, a radially projecting rod on the cone-shaped member, a first pin rockably mounted in the valve body and having a flat lift-face engaging the pin for lifting the rod when rocked in either direction, a second pin rockably mounted in the valve body and having an eccentric projection engageable with the shoulder only

when rocked in one direction, and handle means mounted on the pins for rocking them.

5. A valve for controlling the flow of fluids comprising a valve body having first and second passages extending therethrough, said first passage being constricted intermediate its ends in the provision of a valve seat, a tubular spout slidably mounted in one end of said first passage and projecting inwardly beyond the constriction, being provided on such inwardly projecting end with a closure element for valve-forming co-operation with the valve seat, a tubular member mounted in the lower end of said second passage and being provided at its upper end with a valve seat forming end face, a stem loosely and shiftably mounted in and extending through said tubular member, a valve poppet fixed upon the upper end of said stem for co-operation with the seat forming end face, a discharge nozzle mounted on the valve body and projecting downwardly from the tubular member, a downwardly pointed cone-shaped member disposed within the nozzle and being connected to the stem for movement therewith, an abutment shoulder on the spout, a radially projecting rod on the cone-shaped member, a first pin rockably mounted in the valve body and having a flat lift-face engaging the pin for lifting the rod when rocked in either direction, a second pin rockably mounted in the valve body and having an eccentric projection engageable with the shoulder only when rocked in one direction, said pins being axially aligned and projecting outwardly in opposite directions from the valve body and a clevis-shaped, swingable handle rigidly mounted on and extending radially from the projecting ends of said pins whereby said pins may be rocked responsive to swinging movement of the handle.

6. A valve for controlling the flow of fluids comprising a valve body having a passage extending therethrough, a flat-ended tubular member mounted in the lower end of said passage, said member being provided at its upper end with a valve seat forming end face and being interiorly contoured to provide a streamlined constriction through which fluid may flow, a stem loosely and shiftably mounted in and extending through said tubular member, a valve poppet fixed upon the upper end of said stem for co-operation with the seat forming end face, and handle means for lifting the stem and the associated poppet for opening said passage and permitting the flow of fluid therethrough.

7. A valve for controlling the flow of fluids comprising a valve body having a passage extending therethrough, an axially compressible flat-ended tubular member mounted in and projecting from the lower end of said passage, said member being provided at its upper end with a valve seat forming end face and being interiorly contoured to provide a streamlined constriction through which fluid may flow, a stem loosely and shiftably mounted in and extending through said tubular member, a valve poppet fixed upon the upper end of said stem for co-operation with the seat forming end face, and handle means for lifting the stem and the associated poppet for opening said passage and permitting the flow of fluid therethrough.

8. A valve for controlling the flow of fluids comprising a valve body having a passage extending therethrough, a flat-ended tubular member mounted in the lower end of said passage, said member being provided at its upper end with a valve seat forming end face and being interiorly

contoured to provide a streamlined constriction through which fluid may flow, a stem loosely and shiftably mounted in and extending through said tubular member, a valve poppet fixed upon the upper end of said stem for co-operation with the seat forming end face, discharge nozzle-forming means threadedly mounted in and projecting downwardly from the valve body and being in endwise abutment with the lower end of the tubular member for optionally imposing greater or lesser axial pressure on the tubular member depending upon the relative position to which said means is screwed into the valve body thereby producing a corresponding increase or decrease in the amount of constriction in the interior of said tubular member, and handle means for lifting the stem and the associated poppet for opening of said passage and permitting the flow of fluid therethrough.

9. A valve for controlling the flow of liquids comprising a valve body having a first passage extending therethrough and being provided with a valve seat, a spout mounted in said first passage and being provided with a closure element for valve forming co-operation with the valve seat, said valve body having a second passage extending therethrough, a tubular member mounted in and projecting from the lower end of said second passage and being provided at one end with a valve seat forming end face, a stem movably mounted in and extending through said tubular member, a valve poppet fixed upon the upper end of said stem for co-operation with the seat forming end face, and handle means for simultaneously lifting the spout, stem, and associated closure element and poppet for opening both of said passages and permitting the flow of fluids therethrough.

10. A valve for controlling the flow of fluids comprising a valve body having a passage extending therethrough, a flat-ended tubular member mounted in the lower end of said passage, said member being provided at its upper end with a valve seat forming end face and being interiorly contoured to provide a streamlined constriction through which fluid may flow, a stem loosely and shiftably mounted in and extending through said tubular member, a valve poppet fixed

upon the upper end of said stem for co-operation with the seat forming end face, discharge nozzle-forming means threadedly mounted in and projecting downwardly from the valve body and being in endwise abutment with the lower end of the tubular member for optionally imposing greater or lesser axial pressure on the tubular member depending upon the relative position to which said means is screwed into the valve body thereby producing a corresponding increase or decrease in the amount of constriction in the interior of said tubular member, a downwardly pointed cone-shaped member disposed within the nozzle and being connected to the stem for movement therewith, and handle means for lifting the stem and the associated poppet for opening of said passage and permitting the flow of fluid therethrough.

11. A valve for controlling the flow of fluids comprising a valve body having first and second passages extending therethrough, said first passage being contoured to provide a valve seat, a tubular spout slidably mounted in said first passage, a first closure element provided on said spout for valve-forming co-operation with the valve seat, a tubular member mounted in said second passage and being provided at one end with a valve seat-forming end face, a stem shiftably mounted in and extending through said tubular member, a second closure element provided on said stem for co-operation with the seat-forming end face, and means for simultaneously moving the spout, stem, and the associated first and second closure elements for opening both of said passages and permitting the flow of liquids therethrough.
